UNITED STATES PATENT OFFICE.

THOMAS J. EDWARDS, OF MELROSE, AND WALTER P. OSGOOD, OF MALDEN, MASSACHUSETTS, SAID OSGOOD ASSIGNOR TO SAID EDWARDS.

EMBOSSING AND PRINTING MACHINE.

1,155,999.

Specification of Letters Patent.

Patented Oct. 5, 1915.

Application filed November 18, 1912. Serial No. 732,013.

To all whom it may concern:

Be it known that we, THOMAS J. EDWARDS and WALTER P. Osgood, citizens of the United States, residing at Melrose, in the county of Middlesex, State of Massachusetts, and at Malden, county of Middlesex, State of Massachusetts, respectively, have invented a certain new and useful Improvement in Embossing and Printing Machines, of which the following is a specification, reference being had therein to the accompanying drawings.

The invention has for its object to provide means to feed prepared gold, silver, aluminum, and other transfer material, including color, in an embossing or printing machine into position between the work-support or backing and the embossing or printing-die or surface, so that the required imprint in gold or the desired other material or color may be produced upon the work.

The invention consists essentially in the combination, in an embossing or printing machine, with a work-support or backing and a printing-die or surface, of means for feeding the prepared gold, etc., between the work-support or backing and die or surface so as to intervene between the work and said die or surface.

30 An embodiment of the invention in the preferred form is shown in the drawings, in which latter,—

Figure 1 is a side elevation of an embossing machine having the said embodiment applied thereto. Fig. 2 is a view thereof in section along the line 2, 2, of Fig. 3. Fig. 3 is a plan view of the machine. Fig. 4 is a view of the machine mainly in front elevation, but partly broken away and partly in section along the line 4, 4, of Fig. 3. Fig. 5 is a front elevation of a second form of picker. Fig. 6 is a plan view thereof.

The embossing machine shown is constructed with a frame 1. A backing 2 for the work is constituted by the head of a ram 3. The latter is supported partly by means of a link 4, to the upper portion of which it is pivoted at 5, the link being pivoted by its lower end to the machine-frame at 6, and partly by means of the plunger 7, having at its rear end a strap fitted to an eccentric 8 on the main shaft 9 of the machine. The cylindrical shank of the ram is entered into a chamber in the said plunger, as shown by dotted lines in Fig. 2. It is backed up by

an expanding spiral spring 14^b, Fig. 2, to give yielding and prolonged pressure of the backing against the work when the eccentric 8 moves the plunger forward. A suitable band-pulley 10 is mounted upon the said 60 shaft 9. In practice, clutch-devices and a controlling treadle therefor will be employed for connecting the said pulley to the said shaft at will, to cause a rotation of shaft 9 and an embossing or printing action 65 to take place, and the machine to then come to rest with the backing 2 separated from the die, in readiness for a second operation. A yoke-shaped forward extension 11 of the machine-frame supports an electric-heater 70 12, the body of which constitutes a support for the embossing die 13. The said electric-heater or die-holder, and the die, are located within the recess of the yoke, and the die faces rearwardly. The acting surface of the 75 die is vertical, and so is that of the backing 2, to provide for the insertion of the work to be embossed or imprinted, for instance the top portion of the upper of a shoe, in a vertical position from below, the front lower 80 portion of the machine-frame 1 being constructed to give clearance to the work and avoid interference therewith, thus permitting the work to be inserted as stated and the lower part thereof to occupy a position 85 below the die 13 and backing 2.

The invention provides means for feeding prepared gold or other transfer material, from a source of supply into a position between the backing 2 and the die 13, so that 90 the said material shall intervene between the work and the die, and so that by the closing of the backing and die together the work and the said material shall be compressed together between the backing and the die. The prepared gold, for instance, in the form in which we employ it is in the shape of a slip of sheet material, as paper, having a superficial coating or layer of the gold. A supply of slips is placed upon or within a suitable holder therefor and the slips are successively fed into position adjacent the die. We preferably employ a carrier, and means for feeding the slips in succession from the supply-holder to said 95 carrier, the latter acting to place each slip in turn in the said position. The feeding means, in the prepared embodiment thereof, comprises, essentially, a separator, which may be in the form of a picker, preferably 100 105 110

pneumatic, and a transferrer which transfers the separated slip to the carrier.

In Figs. 2 and 4 a supply of prepared slips *a* is shown supported by a shelf 14 occupying an elevated position in the machine, and carried by a supporting arm 14*. Opposite pneumatic pickers are shown at 15, 15, they being elastically mounted through being carried by opposite arms of a bent leaf-spring 16 extended transversely of the machine, the middle of the said spring being attached to the forwardly-projecting arm of a carrier 17 which is pivoted at 18 upon a support 19. Pipes 20, 20, connect the pickers with a chambered portion of carrier 17, the chamber having an outlet which is in communication by means of a flexible tube 21 with the cylinder 22 of a suction pump, the piston-rod 23 of which is connected to the pin of a crank-arm 24 fast upon a shaft 25 driven by gearing 26, 27, from the main shaft 9. To cause the pickers to touch the surface of the top slip of the pile resting on the shelf 14, and then lift the same to separate it from the next succeeding slip, the carrier 17 is given a rocking movement. This rocking movement is occasioned in the present instance through the engagement of the stem of a screw 28 within the slot 29 extending lengthwise of one member 30 of a two-part extensible connecting link 30, 31, having its other member 31 connected by a pivot 32 to the actuating slide 33 of the transferrer. The member 31 is slotted longitudinally at 31*, 31*, to receive the stems of the screws 30*, 30*, which secure the two members adjustably together. The said slide 33 is actuated in one direction, namely, to lift the pickers from the pile of slips, through the contact of a cam 34 that is carried by shaft 25 with a roll 35 mounted upon the said slide 33, the slide being moved in the opposite direction, to allow the pickers to descend upon the top of the pile, by the tension of a contracting spiral spring 36, Figs. 2 and 3, which engages with one arm, 37, of the transferrer, to which arm the forward end of the slide 33 is pivoted by a screw 38.

In order that the movements of the picker-carrier and pickers toward the pile *a* may vary to suit the height of the top of the said pile, the longitudinal slot 29 is provided in the connecting link 30, 31. In the rearward movement of slide 33 and link 30, 31, one end-wall of the slot 29 encounters the screw 28 and turns the picker-carrier to raise the pickers and the slip engaged thereby, the tops 37*, 37*, of the transferrer arms passing in between the said slip and the remainder of the pile *a*. The slip is detached from the pickers during the ascent of the latter by means of an overhanging piece 38* projecting forward from a bracket of support 19 over the pile *a*. This detaching piece 38* is located at such height above the shelf that

as the picker-carrier and pickers rise, taking a slip with them, the slip is lifted high enough to permit the passage of the transferrer 37 between it and the pile, before the encounter of the slip with the detaching piece disengages it from the pickers. When the slide 33 is moved forward, producing a forward movement of the transferrer which carries forward the separated slip, the picker-carrier is permitted or caused to rock so as to carry the pickers into contact with the top slip of pile *a*. This rocking may be due to the gravity of the forward portion of the picker-carrier, aided by a spring if desired, or a spring may be chiefly depended upon. In Figs. 1 to 4 gravity is relied upon, but in Fig. 6 an expanding spiral spring 29* is shown confined between a projection 29* from member 30 and the head of screw 28. Said spring is threaded upon a pin 29* secured in said projection and working in a hole through said screw-head. The spring acts expansively to hold the screw 28 in contact with the forward end of slot 29. When, however, the pickers encounter the top of the pile *a* in their descent, the spring 29* yields to the resistance which opposes further descent of the pickers.

The transferrer comprises opposite arms 37, 37*, attached to and rising from a small supporting shaft 39. The upper ends of these arms are in the form of curved segments 37*, 37*, which are notched upon their tops, as shown best in Fig. 2, to receive the end-portions of the upraised slip. The notched portions of the transferrer pass beneath the ends of the upraised slip before the slip is detached from the pickers, and the detached slip rests within the notches. The transferrer then is swung forward to deliver the slip to the carrier.

The carrier shown at 40 comprises opposite side-arms that are mounted pivotally upon a small cross-shaft 40*, Fig. 2. Each of such side-arms is provided with a slip-holder or clip 41 constituted by a strip of spring-metal bent upon itself so that the end-portions of a slip carried forward by the transferrer may enter between the two portions of the slip-holder. The carrier is actuated to move forward into its position in the drawings by means of a cam 42 on shaft 25 engaging a roll 43 carried by a slide 44, which latter is pivoted at its front end by screw 45 to one arm of the carrier. A contracting spiral spring 46 which is engaged with the said slide acts to move the carrier rearward to receive a slip. At 50, 50, are side-guides supported from the support 19, and having slotted guideways along which the ends of the slip pass while the slip is being advanced by the transferrer. These guides prevent the slip from becoming separated from the transferrer, and conduct its end-portions into the clips of the carrier.

The support 19 for the shelf 14 is attached to the plunger 7, and the transferer and carrier are both pivoted to the base-portion of the said support. Hence the picker-carrier and pickers, shelf, transferer, and carrier all accompany the plunger, ram, and backing 2 in the backward and forward movement of these latter.

To enable the shelf 14 to be adjusted vertically to suit the size of the pile α , the arm 14^a of such shelf has its lower and rearward extremity entered into a vertical slot 60 of support 19. A rearwardly projecting stud carried by the said arm is connected by a link 61 to a crank-pin 62 on a knurled adjusting wheel 63 which is mounted pivotally upon the support 19. This wheel may be rotated by hand conveniently from time to time whenever the top of the pile α requires to be raised or lowered to bring it into proper position with relation to the pickers.

The pickers may be composed of short sections of rubber tubing set so as to diverge slightly from each other, as in Fig. 4, but preferably we employ the construction shown in Figs. 5 and 6. In the latter construction the pickers 15^a, 15^b, may be composed entirely of metal. They are separately formed and are mounted pivotally upon the picker-carrier 17^a by means of a screw 15^b, located between the two pickers and engaging with ears of the latter projecting inwardly from the upper portions of the pickers. The opposite ends of a leaf-spring 15^c attached to the picker-carrier 17^a bears upon the tops of the pickers and holds them in the depressed position relative to each other and to the picker-carrier that is represented in Figs. 5 and 6. In the case of both constructions, when the pickers in their descent take bearing upon the top slip α they spread apart more or less, swinging outward away from each other and slipping or sliding upon the top surface of the top slip α . As the picker-carrier is swung reversely and the pickers rise, they spring toward each other again, and this produces a buckling upward or downward of the top slip between the pickers, separating such slip from the next succeeding slip and affording opportunity for the entrance of air between the two slips to facilitate the separate lifting of the top slip.

By the curved guideways 50, 50, the ends of the slip that is being transferred are conducted to the carrier so that the entrance of such ends into the openings of the carrier clips is assured, and failure to enter, as on account of the slip being bent or its ends being dropped, is obviated. In the rearward movement of the carrier the upturned extremity of a clip strikes upon the forward end of the corresponding guide 50. This opens the clips. In the subsequent forward movement of the carrier, as the clips leave

the guides 50, 50, the free portions of the clips close upon the ends of the slip so as to hold the said ends firmly.

Mounting the carrier and other parts upon the plunger 7 enables the carrier in its descent with a slip to carry the latter down sufficiently to the rear of the die to clear the die. The carrier then moves forward in unison with the ram or backing, its clips being thereby advanced clear of the work so as to carry the slip to the die. The transferer and the shelf 14 are mounted upon the plunger in order that they may accompany the carrier in its movements, which renders it easier to maintain proper working relationship of the transferer with respect to the carrier, and of the transferer and shelf with respect to each other. The advance of the carrier relative to the die carries the slip against the die and bends the slip somewhat, drawing the ends of the slip out of the clips of the carrier just as the impression is taken. This enables the carrier to rise and move rearward toward the transferer to receive another slip, this movement being permitted by reason of the detachment of the slip which has just been fed from the carrier.

The machine stands at rest with the carrier elevated a short distance above the die, and containing a slip in readiness for the next impression or printing operation. When the treadle is pressed upon to call the machine into action for an embossing operation, the carrier moves down the short distance required to place the slip in front of the die, and when the carrier has become detached from the slip it moves back to the transferer, receives a fresh slip therefrom, and resumes its position just above the die. This position holds the slip sufficiently removed from the heated die to protect the slip from the heat of the die while the machine is standing still. The prepared slip of gold is more or less saturated with paraffin, which would melt if the slip were allowed to keep a position close to the die while the machine is not in action.

The special features of the pickers herein shown and described form the subject of a divisional application.

We claim as our invention.

1. An embossing or printing machine having, in combination, a work-backing, a printing die or surface, a holder for a stack of prepared transfer material in slip form, a carrier to place a slip in position between the backing and the die or surface, so as to intervene between the work and said die or surface, and means for feeding the slip from said stack to said carrier.

2. An embossing or printing machine having, in combination, a work-backing, a printing die or surface, a holder for a stack of prepared transfer material in slip form,

a separator for separating the leading slip of the stack, and means whereby a separated slip is presented in position between the backing and the die or surface so as to intervene between the work and said die or surface.

3. An embossing or printing machine having, in combination, a work-backing, a printing die or surface, a source of supply for prepared transfer material in slip form, a separator for the slips, a transerrer for a separated slip, and a carrier receiving such slip from the transerrer and presenting it in position between the backing and the die or surface, so as to intervene between the work and said die or surface.

4. An embossing or printing machine having, in combination, a work-backing, a printing die or surface, a source of supply for prepared transfer material in slip-form, a pneumatic picker for separating the first slip, a transerrer taking the separated slip, and a carrier receiving the slip from the transerrer and presenting it in position between the backing and the die or surface, so as to intervene between the work and said die or surface.

5. An embossing or printing machine having, in combination, a printing die or surface, a work-backing, an operating plunger for one of such parts, a source of supply for transfer material, and means carried by said plunger operating to transfer

such material from the supply into position between the work and the die or surface. 35

6. An embossing or printing machine having, in combination, a printing die or surface, a work-backing, an operating plunger for one of said parts, a holder for a supply of transfer material, a carrier for presenting a strip of such material between the work and the die or surface, and means for feeding such strip from said holder to said carrier, with the holder, carrier, and feeding means movable in unison with the 45 plunger.

7. An embossing or printing machine having, in combination, a printing die or surface, a work-backing, an operating plunger for one of said parts, a holder for a supply 50 of pieces of transfer material, a separator for the leading piece of such material, a transerrer for such piece, and a carrier receiving such piece from the transerrer and presenting the same between the work and the die or surface, with the holder, separator, transerrer, and carrier movable in 55 unison with the plunger.

In testimony whereof we affix our signatures, in presence of two witnesses.

THOMAS J. EDWARDS.
WALTER P. OSGOOD.
